RATION OF PENNSYLVANIA.

IGNITION SYSTEM FOR INTERNAL-COMBUSTION ENGINES.

1,290,504.

Specification of Letters Patent.

Patented Jan. 7, 1919.

Application filed April 10, 1917. Serial No. 160,994.

To all whom it may concern:

Be it known that I, WILLIAM C. BRINTON, Jr., a citizen of the United States, residing at Kennett Square, county of Chester, and 5 State of Pennsylvania, have invented a new, and useful Improvement in Ignition Systems for Internal-Combustion Engines, of which the following is a full, clear and exact description, reference being had to the 10 accompanying drawings, which form a part of this specification.

The object of my invention is to provide, for internal combustion engines in which the charge in each cylinder is ignited by a 15 plurality of sparks, an ignition system which will insure the absolutely simultaneous production of sparks of equal intensity, thereby insuring the most perfect ignition of the entire charging mixture. This object is accomplished successfully by means of the construction set forth and claimed in an application filed by me November 7, 1916, Serial No. 129,933, wherein, among other features, two separate distributers are employed. 20 The object of the present invention, more specifically stated, is to accomplish the same result by so correlating the distributers that they constitute, in effect, a compound distributer which, if desired, can be confined 25 within a space approximately no greater than that occupied by the ordinary distributer now in use. The present invention, therefore, embodies the subject-matter of the above-named application, but is an improvement thereon.

A preferred embodiment of the invention is shown in the accompanying drawings, in which—

Figure 1 is a vertical section through the 40 distributer.

Fig. 2 is a plan view of the same with part of the cap cut away.

Fig. 3 is a diagram of the ignition system, including the connections to a single cylinder.

A source of current supply α , which may be assumed to be a storage battery, is grounded at one side while its other side is connected with the two primary coils y, y , corresponding to the two spark plugs of each engine cylinder. The coils y, y are arranged in series, the current passing through

them and thence through the contact maker and interrupter a and condenser b to ground.

The two primary coils y, y energize respectively the coils z, z of two secondary circuits. In each secondary circuit is a distributor (as hereinafter described). Each distributor is provided with six terminals adapted for connection respectively with six engine cylinders; each terminal being connected with one spark plug only. The six terminals of the other distributor are also adapted for connection respectively to the same six engine cylinders but to the other 65 spark plugs. In Fig. 3 w represents one of the cylinders and u and v the spark plugs connected respectively to the two distributors.

I have not shown the main switch for closing the primary circuit, as a switch of any convenient type may be employed. Nor is the invention limited to the employment of any particular means for interrupting the current in the primary circuit, which may be accomplished either by a contact maker and interrupter or by a vibrator, or by both alternatively, as set forth in the application above named. In the present disclosure, I have shown a contact maker of the type set 70 forth in the application of Brown and Brinton, Serial No. 38,225, filed July 6, 1915. The same comprises, in general, a cam d on the shaft c (which carries the distributor and which is operated from the engine in 75 the usual way), a sliding contact e and a yielding contact f .

The contact maker and interrupter is mounted within, and on the base of, the distributor box g . The top of the box, near 80 its circumference, carries six terminals h , and the circumferential wall of the box carries six terminals i ; the terminals h being connected with the several spark plugs u and the terminals i with the several spark 85 plugs v . The top of the box, near its center, carries two terminals j and k connected respectively with the two secondary coils z, z .

Supported on the top of shaft c , within 100 the distributor box, is a head m , which, like the walls and top of the box, is of insulating material. The top of this head carries an annular conducting or distributor plate

n with which the terminal *j* has rubbing contact, this being conveniently afforded by making the lower end of terminal *j* tubular and inserting therein a contact pin *l* 5 pressed downward by a spring confined within the tube back of the pin. The plate *n*, in its rotation, approximates successively the several terminals *h*, causing the secondary circuit to jump the slight gaps and 10 close the circuit through the several spark plugs *u* successively.

The terminal *k* is secured to a conducting plate *o* secured against the inner wall of the top of the distributor box. The plate *o* 15 carries, or contacts with, a pin *p* extending along the axis of the shaft *c* and confined within a tube *q* of insulating material secured to the head *m*. Both the tube *q* and pin *p* extend partly through the head 20 *m*. The lower end of the pin *p* extends through a distributor plate *r* and contacts with the free end of a leaf spring *s* secured to the under face of the plate *r*. The head *m* is cut away radially to accommodate the 25 plate *r*, which is secured to the head and which, in its rotation, approximates successively the several terminals *i* and causes the secondary circuit to be closed through the several spark plugs *v*.

30 With a two, four, eight or twelve cylinder engine, the number of terminals will, of course, be changed to correspond.

It is obvious that the invention is not limited to any particular numbers of sets 35 of terminals, as the number will vary with the number of spark plugs in each cylinder. The simplest embodiment of the invention, however, is of course one adapted to cylinders each containing only two spark 40 plugs, and I have therefore selected this embodiment for illustration and description.

While I have described the invention as comprising two distributors inclosed in a 45 single box, it is clear that the two are not duplicates, but that the construction of each is modified to adapt it to the other. The two distributors, therefore, from one point of view, may be regarded as constituting 50 one compound distributor.

The sparks produced at the two plugs of each cylinder will both be simultaneous and of maximum intensity.

Having now fully described my invention, 55 what I desire to claim and protect by Letters Patent is:—

1. In an ignition system for internal combustion engines, in combination, an engine cylinder, a plurality of spark plugs therein, 60 a primary electric circuit, means to interrupt the current in the primary circuit, a distributor box, a shaft extending within the box, terminals on the box connected with the respective spark plugs, distributor 65 plates within the box turning with the shaft

and in operative relation one with one spark plug terminal and the other with the other spark plug terminal, other terminals on the box connected with the respective distributor plates, and means actuated by the interruption of the primary circuit to induce a flow of secondary current simultaneously through the last named terminals respectively and their corresponding distributor plates and spark plugs. 75

2. In an ignition system for internal combustion engines, in combination, an engine cylinder, a plurality of spark plugs therein, a primary electric circuit, means to interrupt the current in the primary circuit, a 80 distributor box, a shaft extending within the box, terminals on the box connected with the respective spark plugs, distributor plates within the box turning with the shaft and in operative relation one with one spark plug terminal and the other with the other spark plug terminal, said plates being located in parallel planes spaced apart, other terminals on the box connected with the respective distributor plates, and means 85 actuated by the interruption of the primary circuit to induce a flow of secondary current simultaneously through the last named terminals respectively and their corresponding distributor plates and spark plugs. 95

3. In an ignition system for internal combustion engines, in combination, an engine cylinder, a plurality of spark plugs therein, a primary circuit, means to interrupt said circuit, primary induction means in said circuit, secondary circuits, corresponding in number to the spark plugs, in operative correlation with said induction means, a distributor box, terminals on the box connected with the respective spark plugs, other terminals on the box connected with the respective secondary circuits, a shaft extending within the box, and distributor plates within the box turning with the shaft, one distributor plate being in operative correlation with 100 one terminal of a set and the other distributor plate being in operative correlation with the other terminal of the same set, said distributor plates in their rotation adapted to 105 simultaneously close the respective secondary circuits through the respective spark plugs. 110

4. In an ignition system for internal combustion engines, in combination, an engine cylinder, a plurality of spark plugs therein, 115 a primary circuit, means to interrupt said circuit, primary induction means in said circuit, secondary circuits, corresponding in number to the spark plugs, in operative correlation with said induction means, terminals connected with the respective spark plugs, terminals connected with the respective secondary circuits, a shaft, distributor plates turning therewith, means to maintain 120 electrical connection between the terminals 125 130

of one set and said plates respectively, the terminals of the other set being arranged to simultaneously close the respective secondary circuits through the respective plates 5 in the rotation of the latter.

5. In an ignition system for internal combustion engines, in combination, an engine cylinder, a plurality of spark plugs therein, a primary circuit, means to interrupt said 10 circuit, primary induction means in said circuit, secondary circuits, corresponding in number to the spark plugs, in operative correlation with said induction means, a distributor box, a shaft extending within the 15 box, terminals on the box connected with the respective secondary circuits and arranged relatively close to the axis of the shaft, terminals on the box connected with the respective spark plugs and arranged 20 relatively far from the axis of the shaft, distributor plates turning with the shaft, and means maintaining electrical connection between each plate and its corresponding terminal of the first set, said distributor plates 25 in their rotation simultaneously approximating the respective terminals of the second set.

6. In an ignition system for internal combustion engines, in combination, an engine 30 cylinder, two spark plugs therein, two secondary circuits, a distributor box, a shaft extending within the box, a head on the shaft, two terminals on the box connected with the two secondary circuits respectively and

arranged relatively close to, and on opposite 35 sides of, the axis of the shaft, two terminals on the peripheral part of the box connected with the two spark plugs respectively, two distributor plates carried by the head on the shaft, a pin located axially of the shaft and 40 contacting with one distributor plate, a plate connecting said pin and one of the first named terminals, and a spring pressed pin connecting the other distributor plate and the other of the first named terminals, said 45 two plates, in their rotation with the shaft, approximating the two respective second named terminals.

7. In an ignition system for internal combustion engines, a compound distributor 50 comprising a plurality of series of terminals, a shaft, a plurality of distributor plates rotating with the shaft, each adapted to successively approximate the terminals of one series only, a plurality of terminals corresponding in number to the number of distributor plates, and means establishing electrical connection between the last named terminals and the distributor plates respectively, whereby electric circuits may be 55 closed simultaneously through the last named terminals and the distributor plates and a corresponding number of the first named terminals of as many different series.

In testimony of which invention, I have 60 hereunto set my hand, at Philadelphia, Penna., on this 6th day of April, 1917.

WILLIAM C. BRINTON, JR.
